3,083,654 MATTRESS SEWING TABLE

James A. Cash, Sr., Louisville, Ky., assignor to James Cash Machine Co., Louisville, Ky., a corporation of Kentucky

Filed Jan. 8, 1960, Ser. No. 2,322
24 Claims. (Cl. 112—3)

This application is a continuation-in-part of my co-pending application, S.N. 773,368, filed Nov. 12, 1958, now abandoned.

In covering mattresses, the conventional practice comprises: (1) covering the bottom and peripheral border faces of the mattress with a shallow pan-like cloth cover, having a bottom face panel and a border panel sewn together along the bottom edge of the mattress; and then (2) closing the mattress by sewing a top face panel to the border panel along the top edge of the mattress.

The closing operation is less difficult to perform along the first two edges of the mattress because the top face panel is relaxed but it becomes progressively more difficult to perform along the last two edges because the operator must now stretch the top face panel tightly across the mattress and hold it in this tightly stretched condition while he conducts the sewing operation in order to end up with a mattress having its top face panel tightly stretched to a smooth unwrinkled condition. In closing a full mattress, the operator must initially pull, push or otherwise manipulate it into an approximately centered position wherein its upper peripheral edge usually is inaccurately aligned with the path of the sewing head. In closing a smaller mattress, he must first manually manipulate it into one position, which is offset toward one side of the table, and then manually shift and manipulate it into another position, which is offset toward the other side of the table. The energy and care required by the closing operation necessitates the use of highly skilled labor, subjects that labor to fatigue and slows down production time.

The principal object of this invention is to overcome one or more of the foregoing difficulties in closing a mattress and, more particularly, substantially reduce the energy, care and skill required in the performance of the mattress cover-closing operation, lessen the possibility of fatigue and speed up the operation generally.

Another important object is to provide a method of and a means for supporting a mattress during the closing operation which eliminates the necessity of stretching the top face panel and yet insures the production of a closed mattress having its top face panel tightly stretched to a smooth unwrinkled condition.

Another important object is to provide a mattress cover closing table capable of achieving the foregoing objectives with mattresses of different sizes.

Another important object of the present invention is to provide an easier, quicker and more accurate way of centering any mattress in its first operative position on the table.

Another important object is to provide an easier, quicker and more accurate way of shifting and centering an undersized mattress in its second offset position even while the mattress remains in its elevated position.

Still another important object of the invention is to provide a simple and effective selectively-operable means for actuating the mattress sewing apparatus in a manner allowing the operator to remain adjacent the carriage throughout the mattress closing operation.

Broadly speaking, the first aspect of my invention resides in the concept of performing the closing operation while the mattress is supported in a sagging condition so that its top face panel may be relaxed throughout the entire closing operation. By elevating all margins of

2

the mattress and leaving its center sag, it becomes unnecessary to stretch the top face panel during the closing operation but, at the end of that operation, when the mattress is allowed to flatten out, it will automatically stretch the top face panel into a smooth unwrinkled condition.

In carrying out this aspect of my invention, I propose to support a mattress, during the cover closing operation, by means of a table top composed of relatively elevated sections which are arranged to engage the bottom face margins of a mattress placed thereover and, through such engagement, to support said mattress in a sagging condition. Preferably, the table top sections are hinged for movement from a horizontal position in which they cooperate to provide a flat-faced mattress-supporting surface to a relatively upwardly inclined position in which they engage said mattress marginally and support it in a sagging condition.

For use in closing a full-sized mattress, the table may be provided with a hinged section along each of its four margins. In order to accommodate mattresses of the same length but smaller width, it is only necessary to provide a pair of hinged intermediate sections paralleling the marginal side sections with one intermediate section cooperating with one marginal side section to support the mattress on one side of the table and with the other intermediate section cooperating with the other marginal side section to support the mattress on the other side of the table.

The second aspect of my invention resides broadly in the concept of performing the mattress centering and shifting operations mechanically. The mechanical performance of these operations makes it easily and quickly possible to center each full mattress accurately in its centrally disposed operative position on the table and to center an undersized mattress accurately in each of its offset positions and to shift it quickly from one offset position to the other. Furthermore, it becomes possible for the operator to institute and control all of these mechanical operations from the carriage.

In carrying out the mattress centering and shifting aspects of my invention, I provide the apparatus (a) with spaced mattress centering means mounted on the table and operable, when actuated, to move from an out-of-the-way position to a relatively raised centering position during which movement they cooperatively engage the border of a mattress and push it into a centered position; (b) with shifting means mounted on the table and operable, when actuated, to push an undersized mattress across the table from its first offset position to its second offset position; and (c) multi-control means mounted on the carriage and arranged for selective operation, first, at the starting end of the table, to actuate the mattress raising means and the centering means so as to raise and center either a full sized mattress in its operative position or an undersized mattress in its first offset position, and second, at the other or shifting end of the table, to actuate the shifting means to push an undersized mattress from its first offset position to its second offset position and to actuate the means required to center and support such mattress in its second offset position.

The invention is illustrated in the accompanying drawings wherein:

FIG. 1 is a perspective view of a mattress sewing table constructed in accordance with my invention, this view showing a mattress supported on the table and a tape edge-sewing machine supported on the track surrounding it;

FIG. 2 is a fragmentary section corresponding to one taken on line 2—2 of FIG. 1;

FIG. 3 is a bottom plan view of the mattress sewing table;

FIG. 4 is a vertical transverse section taken on line 4—4 of FIG. 3;

FIG. 5 is a similar section taken on line 4—4 of FIG. 3 but looking in the opposite direction;

FIGS. 6 and 7 are similar to FIG. 5, FIG. 6 having one, 5 and FIG. 7 the other, of the intermediate leaves raised;

FIG. 8 is a fragmentary bottom plan view of another mechanism for operating the marginal leaves of the table;

FIG. 9 is a perspective view of a mattress sewing apparatus embodying this invention, this view showing the 10 starting and mattress shifting ends of the table at the lower left and upper right respectively;

FIG. 10 is a starting end elevational view of the apparatus shown in FIG. 9;

FIG. 11 is a bottom plan view of the table top structure; 15

FIG. 12 is a section taken along line 12—12 of FIG. 11;

FIG. 13 is an enlarged fragmentary section taken on line 13—13 of FIG. 11, this view illustrating the mattress 20 shifting mechanism with the mattress shifting leaf shown in full lines at the end of its inwardly extended mattress shifting movement and shown in dotted lines in its upwardly and outwardly inclined mattress-supporting position;

FIG. 14 is a fragmentary enlarged perspective view showing the control pedals on the carriage in relation to 25 the starting end of the table;

FIG. 15 is a section taken along line 15—15 of FIG. 14 but omitting the pedal nearest the table to show the underlying pedal operated mechanism on the carriage and the co-operating mechanism on the table structure;

FIG. 16 is a section taken along line 16—16 of FIG. 14;

FIG. 17 is an enlarged fragmentary view taken along line 17—17 of FIG. 13;

FIG. 18 is a schematic view of the table leaf operating system, this view including a cut-way top plan view of the table leaves to show the relationship between the 35 operating system and the leaves;

FIG. 19 is an elevational view of the mattress shifting end of the table, this view being partly broken to show a modified form of mattress shifting mechanism;

FIG. 20 is a perspective view of the structure shown in FIG. 19 with the upper portion of the table top and carriage omitted, the lower portion of the carriage being shown at the starting end of the table; and

FIG. 21 is a fragmentary elevational view showing the carriage in operative relationship to the modified form of mattress shifting mechanism.

APPARATUS OF FIGS. 1-7

The mattress sewing apparatus illustrated in FIG. 1 includes: a rectangular base; a sewing machine mounted on the base for travel along an endless rectangular path extending along the rectangular periphery of the base; a mattress supporting table located within said path and mounted on the base, said table having hinged leaves; and operating means for said leaves.

Base

The rectangular base 1 is conventional and includes an upper rectangular trackway, also designated 1, a lower rectangular trackway 2 and a plurality of posts 3, one interconnecting and supporting the upper and lower trackways 1 and 2 at each corner of the base. The sewing machine travels on upper and lower trackways 1 and 2 in moving around the periphery of the mattress sewing table.

Sewing Machine

The sewing machine is conventional and includes: a carriage, also designated 5, movably supported on the upper and lower trackways 1 and 2; a sewing head 6 adjustably mounted on top of the carriage; and a motor 7 mounted on the carriage 5 and operatively connected not only to the carriage for moving it about the base but also to the sewing head 6 for actuating it during the sewing operation.

The mattress sewing table includes: a support frame; and a table top mounted on the frame and having hinged marginal sections and a center section including certain hinged intermediate sections.

SUPPORT FRAME

The support frame 9 includes: at its top, a rectangular frame, also designated 9, the underside of which is seen in FIG. 3; a pair of horizontal cross braces 10 bridging the space between the longitudinal sides of the rectangular support frame 9 at intermediate locations; and a plurality of vertical legs 11, one extending downwardly from each corner of the support frame 9 and mounted on the base 1 for vertical adjustment. The means for adjustably mounting the legs 11 is not shown as it is conventional and is not a part of this invention.

TABLE TOP

The table top 13 includes a plurality of sections overlying the top of the rectangular support frame 9. These sections include: a rectangular center section; and four surrounding marginal sections 14 to 17, one for each side or end edge of the center section. Each marginal section is pivoted to the adjacent edge of the center section for movement between a collapsed position, in which it is horizontally aligned with the center section, and a raised or elevated position, in which it is inclined upwardly and outwardly from the marginal edges of the center section.

MARGINAL SECTIONS

The marginal sections include two end edge leaves 14 and 15 and two side edge leaves 16 and 17. These leaves are pivoted by the hinges 18 to the adjacent side and end edges of the center section of the table. Each of the leaves 14 to 17 is mitered at its opposite ends, as seen in FIG. 3. The adjacent mitered ends, of each pair of leaves at each corner of the table, are separated, in their 40 horizontal positions, by a small gap providing sufficient clearance for the leaves to be raised to their inclined positions.

When the hinged marginal leaves 14-17 are elevated, their uppermost edges are spaced and positioned to engage the corresponding bottom-face margins of a mattress placed thereover and, through such engagement, to support said mattress in a sagging condition. This is illustrated in FIG. 5. To enable each marginal section or leaf 14-17 to be raised and lowered, its bottom face is provided with an operating lever 19, which is rigidly mounted thereon and arranged to extend or project downwardly therefrom.

CENTER SECTION

The center section of the table 13 is composed of a transverse succession of five longitudinal leaves 21 to 25, which extend lengthwise in parallel relationship on the frame 9 with their adjacent side edges narrowly spaced, as seen in FIG. 5. The odd numbered leaves of this succession, namely, the two outer leaves 21 and 25, and the center leaf 23, are stationary and fixed to the table frame 9. The other two intermediate leaves 22 and 24 are pivoted by hinges 26 to the opposite side edges of the center leaf 23.

The intermediate hinged leaves 22 and 24 are arranged in the center section so that they may be alternately raised to an upwardly inclined position to aid in supporting a smaller mattress, such as a twin size mattress, at different times on opposite sides of the table. This alternate use of the leaves 22 and 24 is illustrated in FIGS. 6 and 7.

An individual operating lever 27 is fixed to the bottom face of each of the intermediate hinged leaves 22 and 24. These levers 27 function, when appropriately moved, 75 to raise and lower the leaves 22 and 24.

Operating Means

The operating means for the leaves includes: means for raising and lowering the marginal sections of the top; and means for raising and lowering the intermediate sections of the top.

MEANS FOR RAISING AND LOWERING MARGINAL LEAVES

The marginal leaves 14 to 17 are raised and lowered by a mechanism, which, as seen in FIG. 3, includes: an electric motor 30 mounted on a plate 31 fixed to the bottom of the table frame 9; and a mechanism interconnecting the motor 30 with the levers 19 fixed to the lower faces of the leaves 14 to 17. The interconnecting mechanism, proceeding from the motor 30 to the levers 19, includes: a pinion 32 fixed to the shaft of the motor 30; a gear 33 rotationally driven by the pinion 32; a primary link 34 having one end eccentrically pivoted on the gear 33 and its other end eccentrically pivoted to a spoked wheel 36; and individual secondary links 37 to 40 interconnected between the outer ends of separate spokes of the wheel 36 and individual levers 19.

The small pinion 32 and large gear 33 act as a simple gear reducing mechanism. The eccentric connection of the link 34 to the gear 33, which causes the link 34 to reciprocate when the gear is rotated, is of the ball and socket type allowing a universal pivoting movement.

The spoked wheel 36 is mounted on a suitable bearing axle, which is fixed to and depends from a table cross brace 10. The wheel 36 is composed of bars crossing at right angles to each other to form spokes of equal length. A horizontal flange 43 is fixed to one of the wheel spokes and connected to the end of the primary link 34. Obviously, the reciprocation of the link 34, will oscillate the wheel 36 back and forth. The connection between the link 34 and wheel 36 is of a pin-slot type allowing the magnitude of the angular movement of the oscillating wheel to be adjustably varied and also of a type allowing a universal movement of this end of the link 34, the same as the pivot on the other end thereof.

The secondary links 37 to 40 are adjustable in length and are also mounted on pivots at their opposite ends providing a universal movement. The rotation of the spoked wheel 36 moves the secondary links simultaneously and, therefore, raises or lowers the marginal leaves 14 to 17 simultaneously through their respective operating levers 19.

MEANS FOR RAISING AND LOWERING INTERMEDIATE LEAVES

As best seen in FIGS. 5-7, the power means for operating the intermediate leaves 22 and 24 includes: an electric motor 47 fixed on a plate 48 welded to a table cross brace 10; and a mechanism interconnecting motor 47 with both levers 27 so that the intermediate leaves 22 and 24 can be alternately raised. This interconnecting mechanism includes: a crank wheel 49 fixed to the shaft of the motor 47; a link 50 eccentrically pivoted at one end to the crank wheel 49; and a bridge plate 51 pivoted to the other end of link 50, the plate being connected at its opposite ends to the levers 27.

Each end of the bridge plate 51 has a horizontal slot 52 to receive a pin 53, which is fixed to the levers 27 and arranged to extend through and slide in these slots. The slots 52 are located so that when both of the leaves 22 and 24 are horizontal, as seen in FIG. 5, both of the pins 53 are at the inner ends of their respective slots. As indicated in FIGS. 5-7, movement of the bridge plate 51 in the "right" direction, transverse of the leaves 22 and 24, raises the right leaf 22 while movement in the "left" direction, raises the left leaf 24.

Operation

At some time prior to the operation of the FIG. 1 apparatus, a partially formed mattress cover, having, as indicated in FIG. 2, a bottom face-panel 56 and a border

panel 57 sewn together along their adjacent edges, is applied over a mattress 55. Then this mattress is placed on the table with its uncovered face uppermost. In completing the mattress-covering operation, a top face-panel 59 is placed over the uncovered face of the mattress 55 and its edges are sewn to the adjacent edges of the border panel.

The conventionally rolled edges 58 and 60 of the mattress 55 are similar to each other. The rolled edge 60 is formed by overlapping the edge of the top face-panel 59 and the upper edge of the border panel 57 to form an outwardly extending flange, applying a longitudinally folded tape 61 progressively over these overlapped edges to sandwich them between its folded portions and simultaneously sewing the resulting four-layer assembly together with a seam 62.

At the start of the operation, we assume that all of the pivoted leaves of the table top 13 are down in horizontal positions and that the sewing machine 5 and mattress 55 are ready for the closing operation.

With a full size mattress 55, only the marginal (side and end) leaves 14 to 17 are raised. This is done by energizing the motor 30 to rotate the spoked wheel 36 counterclockwise, as seen in FIG. 3, and thereby push the secondary links 37 to 40 outwardly. This moves the lower ends of the levers 19 outwardly and such movement swings the marginal leaves to their respective inclined positions as seen in FIG. 4. In this position, the bottom face margins of the mattress 55 are engaged and raised by the marginal leaves while the center of the mattress sags downwardly normally remaining on the center section of the table.

The operator pulls the adjacent edges of the top face panel 59 and the border panel 57 into the sewing machine head 6 and proceeds to sew the rolled edge 60 progressively around the mattress. Due to the sag in the mattress 55, the top face panel 59 is loose and relaxed thus relieving the operator of the necessity of stretching it as the rolled edge 60 is stretched.

When the rolled edge 60 is completed, the operator energizes the motor 30 in the opposite direction to rotate the spoked wheel 36 clockwise and drop the leaves 14 to 17 simultaneously to their respective horizontal positions. The ensuing movement of the mattress 55 to a flat position stretches the top face panel 59 of the cover to a smooth condition.

The table is designed to handle smaller size mattresses such as a twin size mattress 65. To start this operation, a twin size mattress 65 is placed on the table with one of its side margins lying on one or the other of the side marginal leaves 16 (or 17) and its other side margin located on a corresponding intermediate hinged leaf 24 (or 22).

The motor 30 is now energized to raise all of the marginal leaves 14 to 17 simultaneously but only three of them (two ends and one side) are brought into engagement with the corresponding margins of the mattress. To engage the remaining side margin of this mattress, the motor 47 is energized to move the bridge plate 51 to the left, as seen in FIG. 5, and thereby raise the "left" intermediate hinged leaf 24. The operator can now proceed to sew three margins, one after the other, namely, one end margin, one side margin and the other end margin.

Thereafter, the motors 30 and 47 are energized to drop the raised marginal and intermediate leaves, the mattress 65 moved across the table to place its unsewn side margin over intermediate section 22 and motor 30 and 47 again operated to raise the margin al leaves and the "right" intermediate leaf 22. The unsewn edge of mattress 65 is now held in an elevated position by the marginal section 17. As soon as this edge is sewn, all table leaves are again dropped to their respective horizontal positions. Once again, the flattening of the mattress 65 will stretch the top face panel to a very taut and smooth condition.

7
MODIFICATION OF FIG. 8

FIG. 8 illustrates a modified mechanism for raising the marginal leaves 14 to 17 in which the electric motor 30 is replaced by a fluid operated motor 47a having a piston 47b, which is connected to the end of the primary link 34. The motor 47a may be operated by either a pneumatic or hydraulic fluid. Along this same line, the motor 47 for operating the intermediate hinged leaves 22 and 24 may be replaced by a suitable fluid operated motor.

An apparatus of the FIG. 8 type with mechanical centering and shifting means on the table and selectively operable controls on the carriage is illustrated and described in FIGS. 9-18.

APPARATUS OF FIGS. 9-18

This apparatus comprises: (1) the same rectangular base; (2) the same sewing machine with its carriage and drive modified; (3) the same hinged leaf table; (4) a mattress centering means mounted on the hinged leaves of the table; (5) mattress shifting means mounted on the table; (6) operating means mounted on the table for actuation from the starting end thereof to raise a full size mattress to and support it in a central elevated position and, when handling an undersize mattress, for actuation first, from the starting end thereof, to raise the undersize mattress to and center and support it in one elevated offset position and second, from the shifting end thereof, to shift the undersize mattress to and center and support it in its other elevated offset position; and (7) selectively-operable multicontrol means mounted on the carriage for actuating said operating means.

Base

The rectangular base remains the same and includes parts 1-3.

Sewing Machine

The sewing machine structure includes a carriage 5 and a sewing head 6 as before. Carriage 5, however, has been modified to include a large operator-supporting platform 5A fixed to the bottom of carriage 5 and extending forwardly and outwardly from its front or leading wall.

The motorized drive means has been modified to include a reversible drive motor connected operatively through a first or "motor" clutch not only to the carriage drive means, which contains a second or "carriage" clutch but also to the sewing machine drive means which contains a third or "sewing head" clutch.

The three clutches thus provided in the driving means enables the operator to open all three clutches, start the motor in the forward travel direction or reverse it and let it idle. By closing the carriage clutch, he can move it around the table in the desired direction to the point where sewing is to start. Here he can institute the sewing operation, whenever desired, simply by closing the sewing head clutch. The specific details of the preferred form of carriage and driving means are not shown here are shown in my copending joint application S.N. 812,940, filed May 13, 1959, to which reference may be had.

Rectangular Table

The table remains the same, hence includes: the support frame parts 9-11; marginal section leaves 14-17, each having an operating lever 19; and center section parts 21-25, including hinged intermediate leaves 22 and 24, each with an operating lever 27. For purposes of convenience in further describing this embodiment, the marginal leaves are designated south, west, north and east marginal leaves, respectively, starting at the lower end of the table, as seen in FIGS. 9 and 18, and proceeding clockwise around it. Hence, the marginal leaves will include the south marginal leaf 14, which is at the starting end of the table, the west marginal leaf 16, the north marginal leaf 15, which is at the shifting end of the table, and the east marginal leaf 17.

8
Mattress Centering Means

In accordance with my invention, each hinged leaf 14-17, 22 and 24 is provided with one or more centering members mounted for movement from an out-of-the-way position, when the leaf is upwardly inclined. The centering members on the raised leaves, in each operative position, operatively engage the mattress to center it.

While the centering means may take any suitable form, in the arrangement illustrated, each is in the form of an elongate bar or flange 70 extending along the length of the leaf and preferably along the upper face plane of its outer free edge. Each bar or flange 70 is hingedly mounted on its leaf for movement between its out-of-the-way and its raised or centering positions. As some of these centering members 70 move upwardly, they may normally be expected to engage the border of a mattress and push it in the direction of the oppositely disposed centering members 70, which cooperate with the flanges doing the actual pushing to grip or clamp the mattress in its centered position and restrain it from moving beyond the centered position. Each centering flange carries an operating lever 71 depending from its under side.

Mattress Shifting Means

In the preferred embodiment of my invention, the shifting of an undersized mattress is effected by mechanically pushing that mattress sidewise from one offset position to the other. Preferably this is done with the mattress in its raised position so that its end margins slide upon the upper margins of the end marginal leaves 14, 15. While this movement may be variously accomplished, it is preferably done by swinging west marginal leaf 16 inwardly toward the other east marginal leaf 17 and continuing this swinging movement until the undersized mattress, such as twin-sized mattress 65, reaches its other offset position wherein its corresponding side margin is supported on said east marginal leaf 17.

Accordingly, the mattress shifting west marginal leaf 16 is arranged for swinging movement from its outwardly-extending, upwardly-inclined or normal raised position through the vertical plane of its hinges to an inwardly-extending upwardly-inclined position corresponding to the shifted position of the mattress and provided, on its under side, with another operating lever 73 for actuating it through its mattress shifting movement.

Operating Means

The operating means comprises: (1) a first operating means arranged for activation and inactivation from the starting end of the table and being operative, when activated, to raise the side and end marginal leaves and operate the centering means associated with such leaves; (2) a second operating means arranged for activation from the starting end of the table and being operative, when activated, to raise the first intermediate leaf and operate the centering means associated therewith, said first operating means being arranged for inactivation from the shifting end of the table so as to lower the first intermediate leaf and inactivate its centering means; and (3) a third operating means arranged for activation from the shifting end of the table, when the second operating means is inactivated, and being operative, when activated, first to shift the mattress and, when the mattress is shifted, next to raise the second intermediate leaf and operate the centering means associated with it, said third operating means being arranged for inactivation from the starting end of the table.

FIRST OPERATING MEANS

The first operating means comprises: (1) marginal raising means operative, when energized, to raise all four marginal leaves 14 to 17 and the mattress centering means associated therewith; and (2) marginal valve means arranged for actuation from the starting end of the table

and operative, when actuated, to energize the marginal raising means.

Marginal raising means.—The marginal raising means includes: a marginal cylinder; a marginal linkage mechanism operably interconnecting the marginal cylinder with each of the four marginal leaves 14 to 17; and four marginal centering cylinders, one mounted on each marginal leaf.

Marginal cylinder.—The marginal cylinder 75 moves between a retracted position, wherein the marginal leaves 14 to 17 are lowered to horizontal positions, and an extended position, wherein the marginal leaves are simultaneously raised to their outwardly and upwardly inclined positions. Preferably, the cylinder 75 is pneumatically operated. It may be a cylinder of the double-acting type as shown in FIG. 8, but it preferably is of the single action type, with its extension being accomplished by air pressure and its retraction by an internal spring. It is mounted on the table frame 9 under the table top at a suitable position for operative connection to the marginal linkage.

Marginal linkage.—The marginal linkage operatively interconnects the marginal cylinder 75 with the operating levers 19 of the marginal leaves 14 to 17. This linkage is essentially the same as that used in the embodiments of FIGS. 1 to 7 and FIG. 8 with certain modifications. It includes, proceeding from the marginal cylinder 75 to the levers 19, a primary link 34 connected to the outer end of the cylinder piston rod 75', a four-spoked wheel 36 pivoted to the table frame 9 to rotate in a horizontal plane under the table top with one spoke being pivoted to the other end of the primary link 34, and respective secondary links 37 to 40 connected between respective spokes of the wheel 36 and the levers 19.

The linkage in the present embodiment is modified, as compared to that shown in the earlier embodiments, by having a socket 34' at an end of the primary link 34 which loosely fits over and seats on the outer end of the piston rod 75' of the marginal cylinder 75. This provides a joint between the piston rod 75' and primary link 34 which automatically separates under the application of a tension or pulling force to that joint. During the dropping of the marginal leaves and the retraction of the marginal cylinder, should the leaves be restrained from dropping, this joint separates and keeps the retraction force of the cylinder 75 from pulling the leaves down. In addition to protecting the table from being damaged, this is a safety feature. If anyone should accidentally get their hands pinched under the marginal leaves, between them and the frame 9, the primary link 34 simply separates from the cylinder 75 and the pinched hands will normally not be seriously injured as the only force resting on them is the weight of the leaves.

All of the secondary links are pivoted to their respective operating levers 19 with the exception of the secondary link 38 connected to the west marginal leaf 16. The connection between this link 38 and its lever 19 is a separable connection to allow the west marginal leaf 16 to be swung upward through its mattress shifting movement. This separable connection is provided by the outer end of the link 38 being bent to a right angle portion 76 and seating this bent portion 76 in a notch in its lever 19. To keep the link 38 from dropping during its separation from its lever 19, it slides in a guide ring 77 fixed on the table frame 9.

Marginal centering cylinders.—The centering cylinder 79 of each marginal leaf 14 to 17 raises and lowers its mattress centering flange 70 between inoperative and centering positions simultaneously with the raising and lowering of the marginal leaves 14 to 17. Each centering cylinder 79 is mounted on the under side of its respective marginal leaf adjacent the operating lever 71 for the flange 70 of that particular leaf and is connected to the lever 71 by a link 80, which is pivoted at its opposite ends to the cylinder 79 and to the lever 71, respectively. The

extension of the cylinder 79 lifts the flange 70 upwardly to its mattress centering position and its retraction drops the flange to an outwardly-extending inoperative position aligned with its leaf. Preferably, the cylinder 79 is pneumatically actuated and of the type whereby air pressure extends its piston and an internal spring retracts it, the same type as the preferred form of marginal cylinder 75.

Marginal valve means.—The marginal valve means includes: a marginal valve controlling the extension and retraction of the marginal cylinder 75 and all four marginal centering cylinders 79; and a marginal valve operating assembly mounted on the table frame 9 for cooperation with controls mounted on the carriage 5.

Marginal valve.—The marginal valve 82, as seen in FIG. 18, is a two position valve operable between an exhaust position, in which it exhausts the marginal cylinder 75 and the marginal centering cylinders 79 to atmosphere, and a pressure position, wherein it feeds air pressure to these cylinders. It is connected on one side to a suitable air pressure source 83 by a supply air line 84 and on its other side to a marginal air line 85 having connections with the marginal cylinder 75 and with each of the marginal centering cylinders 79. In its exhaust position, it disconnects the supply air line 84 from the marginal air line 85, while connecting the latter to an exhaust port in its casing. In its pressure position, it connects the supply line 84 to the marginal air line 85, while blocking the exhaust port. The structure of the marginal valve 82 is conventional and includes an operating plunger 82' which is biased outward by an internal spring to the exhaust position of the valve and movable inwardly (downwardly as seen in FIG. 18) to the pressure position.

Marginal valve operating assembly.—This assembly is mounted on the table at its starting end and is actuated by control means mounted on the carriage 5 to operate the marginal valve 82. It includes a marginal valve mounting means; a marginal valve rocker; and three frame mounted hinged flaps for rocking the marginal valve rocker from the carriage mounted controls.

Marginal valve mounting means.—The marginal valve 82 is mounted at the starting end of the table, intermediate the floor and the table top, on a vertical plate 87 fastened to a pair of horizontal bars 88 extending between the inner edges of the corner posts 3 at that end of the table. It is located with its plunger 82' at its top and projecting upwardly from it, as seen in FIG. 16.

Marginal valve rocker.—The plunger 82' is actuated by a marginal valve rocker 90. The rocker 90 is a vertically extending member which is located over the outer side of the marginal valve 82, opposite its mounting plate 87, and is pivoted on a horizontal axis midway of its upper and lower ends to the plate 87. The rocker 90 includes a tongue at its upper end which is bent over the top of the marginal valve 82 and carries a cam roller 91 for engagement with the valve plunger 82'. The rocker 90 rocks between a neutral vertical position wherein the cam roller 91 is disengaged from the valve plunger 82', and an outwardly-upwardly inclined position, wherein the cam 91 depresses the plunger 82' to move the marginal valve 82 to its pressure position, as seen in FIG. 16. Normally, the rocker will remain in any position to which it is moved.

Hinged flaps.—The rocker 90 is rocked on its horizontal axis by three hinged flaps which include an upper flap 93, center flap 94 and lower flap 95. Each of the flaps 93 to 95 is an elongate horizontal bar extending across the starting end of the base 1 and hinged on horizontal axes to the corner posts 3 at that end of the base. These flaps are probably best shown in FIG. 16.

The upper flap 93 extends across the upper end of the rocker 90, is hinged along its upper edge, and swings inwardly to engage and rock the upper end of the rocker 90 inwardly, in a counter-clockwise direction as seen in FIG. 16, to its exhaust position.

The center flap 94 extends across the lower portion of

the rocker 90, is hinged at its upper edge, and is located slightly inwardly of the upper flap 93. Swinging the lower edge of the flap 94 inwardly engages the rocker 90 and rocks its lower end inwardly to move the valve 82 to its pressure position. This center flap 94 is used to operate both the marginal valve 82 and another valve which is described later.

The lower flap 95 also extends across the lower end of the rocker 90 below the flap 94. However, it is hinged at its lower edge so that its upper edge swings inwardly. It is located somewhat outwardly of the center flap 94. In addition, its inner face contains a projection 96 opposite the rocker 90 which engages the rocker 90 as the flap 95 swings inwardly to rock the lower end of the rocker inwardly and also move the valve 82 to its pressure position. This lower flap 95 is used when only the marginal valve 82 is to be operated.

SECOND OPERATING MEANS

The second operating means comprises: (1) first intermediate raising means operative, when energized, to raise the first intermediate leaf 24 and the centering means associated therewith; and (2) first intermediate valve means operable to neutral and first positions, said first intermediate valve means being arranged for actuation from the starting end of the table to its first position and operative, when so actuated, to energize the first intermediate raising means, and arranged for return to its neutral position from the shifting end of the table to deenergize the first intermediate raising means.

First intermediate raising means.—The first intermediate raising means includes: a first intermediate cylinder connected to the first intermediate leaf 24; and a first intermediate centering cylinder mounted on the first intermediate leaf and connected to the first centering means associated with that leaf.

First intermediate cylinder.—The first intermediate cylinder 97 raises and lowers the first intermediate leaf 24, which is the hinged intermediate leaf nearest the east side of the table. The cylinder 97 is mounted under the table top adjacent the operating lever 27 of the first intermediate leaf 24 and is connected to that lever by a link 98. The link 98 is pivoted to the lever 27 and, at its other end, has a socket fitting over the outer end of the cylinder piston rod, thus providing a separable joint similar to that between the marginal cylinder 75 and the primary link 34.

The extension of the first intermediate cylinder 97 raises the first intermediate leaf and its retraction lowers the leaf 24. The cylinder 97 is similar to the marginal cylinder 75 in that it is extended by air pressure and retracted by an internal spring.

First intermediate centering cylinder.—The first intermediate centering cylinder 79' and its mounting on the first intermediate leaf 24 is the same as the previously described marginal centering cylinders 79. Hence, it is mounted underneath the leaf 24 adjacent the lever 71 of the centering flange 70 of that leaf and is connected to the lever by a link 80. The extension of the cylinder 79' raises the flange 70 and its retraction lowers the flange.

First intermediate valve means.—The first intermediate valve means includes: a first intermediate valve controlling the extension and retraction of the first intermediate cylinder 97 and the first intermediate centering cylinder 79'; and an intermediate valve operating assembly mounted on the table for cooperating with controls mounted on the carriage.

First intermediate valve.—The first intermediate valve 100, looking at FIG. 18, is movable between exhaust and pressure positions. In its exhaust position, it exhausts the first intermediate cylinder 97 and the first intermediate centering cylinder 79' to atmosphere, and in its pressure position, it feeds air pressure to these cylinders. It is connected on one side to the supply air line 84, connected to the air pressure source 83, and on its other side to a first intermediate air line 101 running to the

5

cylinders 97 and 79'. Like the marginal valve 82, it includes a plunger 100' which is biased upwardly and outwardly to the exhaust position and is depressed inwardly to move the valve to the pressure position.

Intermediate valve operating assembly.—This valve operating assembly is mounted on the table and is actuated by control means on the carriage and at the starting end of the table to move the first intermediate valve 100 to its pressure position and, at the shifting end of the table, to move the valve 100 to its exhaust position. This means comprises: an intermediate valve mounting means; an intermediate valve rocker; and a pair of intermediate hinged flaps moved by the control means on the carriage.

Intermediate valve mounting means.—The first intermediate valve 100 is mounted at the starting end of the table beside the marginal valve 82 on another vertical plate 87 which is supported by the horizontal bars 88. Like the marginal valve 82, it is positioned with its plunger 100' at its top.

Intermediate valve rocker.—This rocker 103 is also the same as the marginal valve rocker 90 and is pivoted on a horizontal axis on the plate 87 supporting the first intermediate valve 100. Like the rocker 90, the intermediate rocker 103 carries a roller 91 at its top end which is movable to engage and depress the plunger 100' of that valve. In its normal vertical position, the rocker 103 is in a neutral position. Swinging the upper end of the rocker 103 outward of the table moves the valve 100 to its pressure position.

Intermediate hinged flaps. The rocker 103 is swung on its horizontal axis by a pair of intermediate hinged flaps which include the center flap 94, at the starting end of the table, which is movable inwardly by carriage controls to move the first intermediate valve 100 to a pressure position and a fourth hinged flap 105 mounted at the shifting end of the table for swinging by the carriage mounted controls to return the first intermediate valve 100 to its exhaust position.

The fourth hinged flap 105 is similar to the other flaps 93 to 95, extends across the shifting end of the table and is hinged at its upper edge to the posts 3 at that end of the table to swing on a horizontal axis. It is connected to the lower end of the intermediate rocker 103 by a tie rod 106 having pivoted connections at its opposite ends to the flap 105 and rocker 103, respectively. Swinging the flap 105 inwardly, counter-clockwise looking at FIG. 15, swings the upper end of the rocker 103 inwardly and, if the valve 100 is in its pressure position, moves the valve 100 to its exhaust position by moving the roller 91 of the rocker 103 away from the valve plunger 100'.

THIRD OPERATING MEANS

The third operating means comprises: (1) a second intermediate raising means operative, when energized, to raise the second intermediate leaf 22 and operate the centering means associated therewith; (2) mattress shifting means operative, when energized one way to shift a mattress from the first offset position to the second position; and (3) valve means arranged for actuation from the shifting end of the table and operative, when actuated, to energize the mattress shifting means one way and, after the mattress is shifted, to energize the second intermediate raising means.

Second intermediate raising means.—This means includes: a second intermediate cylinder operably connected to the second intermediate leaf 22, which is the movable intermediate leaf nearest the west side of the table; and a second intermediate centering cylinder operably connected to the centering means of the second intermediate leaf.

Second intermediate cylinder.—This cylinder 108 is similar to the first intermediate cylinder 97 and like the cylinder 97, is connected by a separable joint to a link 98 which is pivoted to the operating lever 27 of the second intermediate leaf 22. Applying air pressure to the cylinder 108 extends it to raise the leaf 22 and ex-

70

75

hausting the cylinder retracts it and lowers the leaf 22.

Second intermediate centering cylinder.—The second intermediate centering cylinder 79" and its mounting on the second intermediate leaf 22 is the same as the previously described centering cylinders 79 and 79'. Hence, it should suffice to say that it is mounted on the underside of the leaf 22 and is connected to the operating lever 71 of the flange 70 of that particular leaf by a link 80. The extension of the cylinder 79" by the application of air pressure thereto raises the flange 70 and retracting it by exhausting it lowers the flange 70.

Mattress shifting means.—The mattress shifting means is operative, when energized one way, to swing the west marginal leaf 16 from its outwardly slanted position to an inwardly slanted position and, through such movement, cause the west marginal leaf 16 to push the mattress to its second offset position, said shifting means being operative, when energized another way to return the west marginal leaf 16 to its outwardly slanted position. The mattress shifting means includes a double acting shifting cylinder 110 connected to the operating lever 73 of the west marginal leaf 16.

Looking at FIG. 13, the cylinder 110 is vertically mounted below the lever 73 with the lower end of the cylinder housing pivoted on a depending bracket fixed to the table frame 9. The outer end of its piston rod is pivoted to the lever 73.

Extension of the cylinder 110 swings the west side marginal leaf 16 upwardly through its mattress shifting movement and the vertical plane to an inwardly-extending upwardly-inclined position. Retracting the cylinder 110 returns the leaf 16 to its former outwardly-extending upwardly-inclined position. Normally, the cylinder 110 is operated only after the leaf 16 has been raised to its outwardly-extending upwardly-inclined mattress cradling position.

As previously mentioned, the cylinder 110 is double acting. This means that it has an extension end and a retraction end and is moved in the extension and retraction directions by alternately applying air pressure to these ends. The speed of the movement of the cylinder 110 is controlled by metering or restricting the flow of air pressure applied to it.

Valve means.—The valve means comprises: a double acting reversing valve means operable, in its normal position, to deenergize the second intermediate raising means and condition the shifting means for energization one way to shift a mattress and, in another position, to condition the shifting means for energization the other way to return it to its normal position and to condition the second intermediate raising means for energization; means for moving the reversing valve from its normal position to the other position at the end of the shifting movement and for returning it to its normal position when the carriage returns to the starting end of the table; and a second intermediate valve means operable to neutral and second positions and operative, in its neutral position, to deenergize both the second intermediate raising means and the mattress shifting means, said second intermediate valve means arranged for actuation from the shifting end of the table to its second position and operative, when actuated, to energize the mattress shifting means and, at the end of the mattress shifting operation, to energize the second intermediate raising means, and arranged for return to its neutral position from the starting end of the table.

Reversing valve means.—The reversing valve means comprises a valve 112 having a fluid pressure inlet and two fluid pressure outlets and being movable between a normal shifting position and an operating position. In the normal shifting position, as seen in FIG. 18, it conditions the mattress shifting means for the mattress shifting operation and deenergizes the second intermediate raising means by connecting the extension end side of the double acting shifting cylinder 110 to its fluid pressure inlet so that it may be energized in the mattress shifting direction

and by exhausting the retraction end of the shifting cylinder along with the second intermediate raising means. In its other or operated position, it reverses its fluid pressure and exhaust connections with the mattress shifting means and the second intermediate means and thereby conditions the mattress shifting cylinder for energization in the return direction and the second intermediate raising means for energization in the raising direction.

Looking at FIG. 18, the valve 112 is connected, at its pressure inlet, to a second intermediate air line 113, at one of its outlets, to an extension air line 114 running to the extension end of the mattress shifting cylinder 110 and, at its other outlet, to a retraction air line 115 which runs to the retraction end of the cylinder 110, to the second intermediate cylinder 103 and to the second intermediate centering cylinder 79". The valve 112 has an internal chamber, also designated 112, holding a shuttle 112' which slides back and forth alternately over the outlets connected to the air lines 114 and 115. The casing of the valve 112 also includes an exhaust port located between the outlets. In each position of the shuttle 112, the chamber 112 is connected with one outlet while the other outlet is connected to the exhaust port, with the connections to the outlets being reversed in alternate positions of the shuttle.

The reversing valve 112 is a conventional pneumatic valve having an internal pneumatic valve moving means controlled by remotely located pneumatic switches for moving it between alternate positions and is sold under the trade name "Meadmatic" by the Mead Specialties Co., Chicago, Illinois.

Reversing valve moving means.—The reversing valve moving means comprises: means providing first and second actuating chambers normally subject to balanced fluid pressures and formed by means including a piston movable one way or the other in response to pressure differentials between said chambers acting in one direction and the other, said piston being connected to move the reversing valve correspondingly between its normal shifting and operating positions; first switch means, positioned to be actuated at the end of the mattress shifting movement, to unbalance the pressure differential in a direction causing the piston operated valve to move from its normal position to its operated position; and second switch means, positioned to be actuated as the second intermediate valve means is returned to its neutral position, from the starting end of the table, to unbalance the pressure differential in the other direction to return the piston operated reversing valve to its normal position.

First and second actuating chambers.—These chambers are located and formed at the opposite ends of a free piston 117 reciprocating in a cylinder bore provided in the casing of the valve 112. As seen in FIG. 18, the left actuating chamber is designated 118 and the right chamber is designated 119.

The free piston 117 includes a small passage 117' extending axially between its ends which normally allows the air pressure in the two actuating chambers 118 and 119 to be balanced. However, this passage 117' is too small for a suddenly applied differential of pressure between the two chambers 118 and 119 to immediately balance. Hence, if one chamber, say 118, is suddenly exhausted, the air pressure in the other chamber 119 biases the piston 117 to the left in the direction of chamber 118.

The piston 117 is connected to the valve shuttle 112' for movement therewith by a stem which is fixed on the shuttle and loosely seats in a radial hole in the piston 117. This radial hole communicates with the passage 117' and allows air pressure to flow from the main chamber 112 of the valve through this radial hole and the passage 117' into the two actuating chambers 118 and 119.

With the shuttle 112' in its normal shifting position, as seen in FIG. 18, the shuttle 112' and piston 117 are positioned to the right and the exhaustion of the left actuating chamber 118 will result in the air pressure in the right

chamber 119 moving the shuttle 112' to the left to its operating position. To reverse the valve, it is only necessary to exhaust the right chamber 119 and the air pressure in the left chamber 118 moves the piston 117 and shuttle 112' to the right, returning the valve 112 to its normal shifting position.

First switch means.—This means is actuated at the end of the mattress shifting movement to exhaust the left actuating chamber 118 and cause the valve 112 to move from its normal shifting position to its operating position. This means is a first vent valve 121 connected by a hose to the left actuating chamber 118 and mounted on the table where it is engaged and opened by a cam 122 mounted on the piston rod of the mattress shifting cylinder 110, at the end of its extension movement. The vent valve 121 is a conventional valve having a plunger 121' which is biased outward to a closed position and is opened simply by depressing the plunger inward. When open, the valve exhausts the left actuating chamber 118 of the reversing valve 112.

Second switch means.—This means is actuated at the end of the mattress sewing operation, with the carriage at the starting end of the table, to exhaust the right actuating chamber 119 and move the valve 112 to the right to its normal shifting position. It is a second vent valve 123 connected by a hose to the right actuating chamber 119 and located on the table over the intermediate rocker 103 to be opened momentarily by its roller 91 as it rocks clockwise, as seen in FIG. 18, to its neutral position. This momentary opening of the second vent valve 123 returns the valve shuttle 112' toward the right to its normal shifting position and resets the valve 112 for another mattress sewing operation.

Second intermediate valve means.—The second intermediate valve means includes: a second intermediate valve controlling the application of air pressure to the reversing valve 112; and a valve operating assembly for operating the second intermediate valve through control means mounted on the carriage.

Second intermediate valve.—The second intermediate valve 125 is movable between exhaust and pressure positions and is arranged for actuation, from the shifting end of the table, to its pressure position wherein it feeds air pressure to the inlet of the reversing valve 112, which is in its normal shifting position, to effect the energization of the mattress shifting means to shift the mattress and, at the end of the mattress shifting operation, return the mattress shifting means to its former position and also effect the energization of the second intermediate raising means. It is returned to its exhaust position at the end of the mattress sewing operation with the carriage at the starting end of the table.

The second intermediate valve 125 is connected on one side to the supply air line 84 and on its other side to the second intermediate air line 113 running to the reversing valve 112. It includes a plunger 125' which is normally biased outward to the exhaust position of the valve and is movable inwardly to the pressure position, the same as the first intermediate valve 100.

Valve operating assembly.—This assembly is the same as the intermediate valve operating assembly operating the first intermediate valve 100. In fact, the second intermediate valve 125 is located in the same casing that houses the first intermediate valve 100. Together, the two valves 100 and 125 form a double acting valve operated by the intermediate rocker 103 which is movable from a neutral position, with its roller 91 located between the two plungers 100' and 125' of the two valves, alternately to either side of the neutral position to move the two valves to their pressure positions alternately. Swinging the rocker 103, as seen in FIG. 15, clockwise from its neutral position moves the first intermediate valve 100 to its pressure position and swinging it counterclockwise moves the second intermediate valve 125 to its pressure position.

The second intermediate valve 125 is normally moved to its pressure position from the shifting end of the table at the same time that the first intermediate valve 100 is moved to exhaust position. This is performed simply by swinging the fourth flap 105 inwardly of the table to rock the rocker 103 counterclockwise from a position wherein its roller 91 depresses the first intermediate valve 100 to a position wherein it depresses the second intermediate valve 125.

10 The second intermediate valve 125 is normally moved to its exhaust position, with the carriage at the starting end of the table at the end of the sewing operation, by swinging the upper flap 93 inwardly in conjunction with the inward swinging of the center flap 94. These two flaps engage and swing the intermediate rocker 103 to a neutral vertical position as seen in FIG. 15. At the same time, they also swing the marginal rocker 90 to its neutral vertical position, thus also moving the marginal valve 82 to its exhaust position. This movement of the intermediate rocker 103 also momentarily opens the second vent valve 123 to return the reversing valve 112 to its normal mattress shifting position.

15 The second vent valve 123 is mounted above the roller 91 of the intermediate rocker 103 approximately midway between its neutral position and the plunger 125', so that the roller 91 opens the vent valve 123 as it is withdrawn from the plunger 125', before that plunger is entirely raised. In other words, the vent valve 123 should be closed when the rocker roller 91 is depressing the plunger 125' its full extent, but should be opened as the plunger 125' raises and before the valve 125 is moved to its full exhaust position. The proper operating point for the vent valve 123 is found by moving it horizontally toward and away from the plunger 125' until the proper operation of the apparatus results.

Carriage Mounted Control Means

20 The carriage mounted control means for selectively operating the first, second and third operating means comprises: (1) first actuating means for actuating, from the starting end of the table, the marginal valve means of the first operating means so as to raise the marginal leaves 14 to 17 and activate the associated centering means; (2) second actuating means for actuating, from the starting end of the table, the first intermediate valve means of the second operating means from its neutral position to its first position so as to raise the first intermediate leaf 24 and activate the associated centering means; (3) third actuating means for actuating, from the shifting end of the table, the first and second intermediate valve means of the second and third operating means, the first intermediate valve means being operated from its first position to its neutral position so as to lower the first intermediate leaf 24 and inactivate the associated centering means, and the second intermediate valve means being actuated from its neutral position to its second position to energize the mattress shifting means one way and thereby shift the mattress from its first offset position to its second offset position, and, upon the completion of the mattress shift and the movement of the valve reversing means to its other operated position, to raise the second intermediate leaf 22 and activate the associated centering means; and (4) fourth actuating means for actuating, from the starting end of the table, the marginal valve means and the second intermediate valve means to return them to neutral positions and thereby drop the marginal leaves 14 to 17, the second intermediate leaf 22 and the associated centering means, the reversing valve means being also returned by this same means to its normal mattress shifting position wherein it is ready for another mattress sewing cycle.

FIRST ACTUATING MEANS

25 The first actuating means operates the marginal rocker 90 to move the marginal valve 82 to its pressure position and raise the marginal leaves 14 to 17. This may be

accomplished by swinging either the center flap 94 or the lower flap 95 inwardly to engage and swing the rocker 90. Which flap is tilted depends on whether the operator also wants to operate the intermediate rocker 103. Tilting the center flap 94 operates both the rockers 90 and 103 while tilting the lower flap 95 operates only the marginal rocker 90, due to the projection 96 carried by the lower flap 95 at a position where it engages and operates the rocker 90 without the lower flap operating the other rocker 103.

The carriage 5 includes a series of four pedals located on its operator-supporting platform 5A. Looking at FIG. 14, these pedals include, from left to right, a first pedal 127, a second pedal 128, a third pedal 129 and a fourth pedal 130. Only the first three pedals 127 to 129 operate the flaps. The fourth pedal 130 controls the main "motor" clutch of the carriage, this clutch being engaged by releasing the pedal 130 in a manner similar to an automobile clutch.

With the carriage at the starting end of the table, the second pedal 128 tilts the center flap 94 and it does this, when depressed, by extending a horizontal rod 131 slidably mounted on the platform 5A outwardly to engage the center flap 94 and swing it inwardly of the base. The rod 131 is extended by cam engagement with the second pedal 128. A spring retracts the rod 131.

Also with the carriage at the starting end of the table, the third pedal 129 tilts the lower flap 95 by extending another horizontal rod 132, when depressed. The rod 132, like rod 131, is extended by cam engagement with the third pedal 129 and is retracted by a spring. The main difference between the rods 131 and 132 is that the operative end of rod 131 strikes the center flap 94 and the end of rod 132 strikes the lower flap 95.

SECOND ACTUATING MEANS

With the carriage at the starting end of the table, the second actuating means tilts the center flap 94 to operate the intermediate rocker 103 and move the first intermediate valve 100 to its pressure position to raise the first intermediate leaf 24. This means is a part of the first actuating means and includes the second pedal 128 and its operating rod 131 which, when extended, tilts the center flap 94.

THIRD ACTUATING MEANS

With the carriage at the shifting end of the table, the third actuating means tilts the fourth flap 105 inwardly to swing the intermediate rocker 103 counter-clockwise, as seen in FIG. 15, moving the first intermediate valve to its exhaust position, to drop the first intermediate leaf 24, and then moving the second intermediate valve 125 to its pressure position. This means is also the same as the first and second actuating means and includes the second pedal 128 and its rod 131 or, alternately, the third pedal 129 and its rod 132. The fourth flap 105 is made wide enough for either of the rods 131 or 132 to strike and tilt it.

FOURTH ACTUATING MEANS

With the carriage at the starting end of the table, the fourth actuating means tilts both the upper flap 93 and the center flap 94 inwardly to return both the rockers 90 and 103 to their neutral positions. This means includes the first pedal 127 which swings a bell-crank 134, pivoted on the carriage, inwardly to strike and tilt the upper flap 93, and the second pedal 128 and its rod 131 which tilts the center flap 94. The bell-crank 134 is retracted by a spring. One of its arms extends under the first pedal 127 to provide the operative connection between the two elements.

The first pedal 127 includes a tongue 135, projecting over the second pedal 128. This tongue 135 depresses the second pedal 128 with the first pedal 127 when the first pedal is depressed. Hence, the fourth actuating means is operated simply by depressing the first pedal 127.

OPERATION

Prior to the start of the operation, we assume that all of the table leaves 14 to 17, 22 and 24 are down in their horizontal positions, providing the table top with a completely flat upper surface, the sewing machine 6 and carriage 5 are located along the starting end of the table and that the apparatus is supplied with all necessary power, including electrical power and air pressure.

The operation of closing a full size mattress 55 is described first. In closing the double mattress 55, only the marginal leaves 14 to 17 are raised. The mattress, ready for closing, is laid on the table in an approximately centered position with the loose top face cover panel 59 on top of the mattress. The marginal leaves 14 to 17 are raised by the operator depressing the pedal 129 to push the rod 132 inwardly, tilt the lower flap 95 inwardly, rock the lower end of the rocker 90 inwardly and depress the marginal valve plunger 82, thus moving the marginal valve 82 to its pressure position. Air pressure flows through the marginal air line 85 to the marginal cylinder 75 and the marginal centering cylinders 79 mounted on the marginal leaves.

The extension of the marginal cylinder 75 rotates the spoked wheel 36 counter-clockwise, looking at FIG. 11, to push the secondary links 37 to 40 outwardly and swing the marginal leaves upwardly, raising the bottom face margins of the mattress with its center sagging. Simultaneously, the extension of the marginal centering cylinders 79 raises the centering flanges 70 on the marginal leaves to a vertical position where they engage and surround the vertical edge margins of the mattress. If the mattress is not centered on the table, the raising of the flanges 70 will force it to a centered position on the marginal leaves.

The operator pulls the adjacent edges of the top face panel 59 and the border panel 57 of the mattress cover into the sewing head 6, clamps the sewing head jaws on these edges and proceeds to close the mattress 55 by operating the carriage and sewing machine to travel clockwise, as seen in FIGS. 9 and 18, around the table from the starting end back to the starting end. This operation of the carriage is normally performed by operating the clutch pedal 130 in conjunction with an electrical switch energizing the carriage drive means.

After completing the closing of the mattress stopping the carriage 5 once again at the starting end of the table, and unclamping the sewing head from the mattress, the operator depresses the first pedal 127 to drop the marginal leaves. Because of the tongue 135 overhanging the second pedal 128, the depression of the pedal 127 also depresses the pedal 128, resulting in moving the bell-crank 134 inwardly to swing the upper flap 93 inwardly and moving the rod 131 inwardly to swing the center flap 94 inwardly. Swinging both the upper end center flaps 93 and 94 inwardly rocks the rocker 90 to its neutral vertical position, moving the valve 82 to exhaust position, whereby the marginal cylinder 75 and centering cylinders 79 on the marginal leaves are retracted. The spoked wheel 36 is returned and the marginal leaves 14 to 17 and their centering flanges 70 are dropped. The closed mattress 5 is then removed from the table and the apparatus is ready to receive another mattress.

The operation of closing a smaller or undersize mattress 65 is next described. In this operation, all of the table leaves are used. The undersize mattress 65, ready for closing, is laid on the table with its western edge lying generally along the west side of the table. With the carriage 5 at the starting end of the table, the marginal leaves 14 to 17 and the first intermediate leaf 24 are raised by the operator depressing the second pedal 128 to swing the center flap 94 inwardly. The lower ends of both of the rockers 90 and 103 are swung inwardly by the center flap 94 and both the marginal valve 82 and the first intermediate valve 100 are moved to pressure positions. This movement of the marginal valve 82 raises

the marginal leaves 14 to 17 and their centering flanges 70, as previously described in connection with the full size mattress closing operation. The first intermediate valve 100 admits pressure to the first intermediate air line 101 to extend the first intermediate cylinder 97 of the first intermediate leaf 24 and the first intermediate centering cylinder 79' on that leaf, resulting in the raising of both that leaf and its centering flange 70. The mattress 65 is now cradled and centered in a sagging position between the marginal leaves 14 to 16 and the first intermediate leaf 24.

The sewing head 6 is clamped on the adjacent cover edges of the mattress and the operator sews clockwise around the mattress until he reaches the shifting end of the table. Somewhere along the shifting end of the table, the operator stops the carriage and disconnects the sewing head from the carriage drive means, by a clutch, so that further movement of the carriage 5 will not drive the sewing head.

The operation of shifting the mattress from the west side of the table to the east side is then performed by simultaneously depressing the pedal 128, or the pedal 129, and operating the carriage forwardly along the shifting end of the table. The depression of one of the pedals 128 or 129 at the shifting end of the table swings the fourth flap 105 inwardly to push the tie rod 106 toward the starting end of the table and rock the intermediate rocker 103 to its opposite position, exhausting the valve 100 and moving the second intermediate valve 125 to its pressure position.

Exhausting the first intermediate valve 100 exhausts the first intermediate cylinder 97 for the first intermediate leaf 24 and its centering cylinder 79', causing that leaf and its centering flange 70 to drop. Simultaneously, the second intermediate valve 125 feeds air pressure through the second intermediate air line 113 to the reversing valve 112, which is positioned in its normal shifting position to feed pressure through the extension air line 114 to the extension end of the mattress shifting cylinder 110. The extension of the mattress shifting cylinder 110 swings the west marginal leaf 16 upwardly through the vertical plane to push the mattress 65 to the east side of the table.

At the end of the extension of the cylinder 110, its cam 122 opens the first vent valve 121, causing the reversing valve 112 to move to its operating position and feed pressure to the retraction air line 115. This simultaneously retracts the mattress shifting cylinder 110, returning the west marginal leaf 16 to its former outwardly inclined position, and extends the second intermediate cylinder 108 for the second intermediate leaf 22 and its centering cylinder 79'', raising both that leaf and its centering flange 70. The mattress is now cradled and centered in a sagging position on the marginal leaves 14, 15 and 17, and the second intermediate leaf 22.

During the shifting of the mattress, the operator drives the carriage at the same speed that the mattress moves. Hence, the sewing head remains stationary relative to the mattress during its shifting. The operator stops the carriage at the completion of the mattress shifting movement, re-engages the sewing head with the carriage drive and proceeds to finish the mattress closing operation, stopping at the starting end of the table.

He then disengages the mattress from the sewing head and drops all of the table leaves by depressing the first pedal 127 to move the rockers 90 and 103 to their neutral positions. Moving the rocker 90 to its neutral position drops the marginal leaves 14 to 17 as previously described in the double mattress closing operation.

Moving the rocker 103 to its neutral position moves the second intermediate valve 125 to exhaust position to exhaust pressure from the reversing valve 112, the second intermediate cylinder 108 and the centering cylinder 79'' of the second intermediate leaf 22, causing that leaf and its centering flange 70 to drop. The same movement of the rocker 103 momentarily opens the second vent valve 123 to reset the reversing valve 112 in its normal shifting

position, so that the next time the second intermediate valve 125 is again moved to its pressure position, air pressure will flow to the extension end of the mattress shifting cylinder 110.

MODIFICATIONS OF FIGS. 19-21

These figures show a modified mattress shifting means using a mechanical linkage operated by the movement of the carriage to swing the west marginal leaf 16 through its mattress shifting movement. This means includes: a linkage; and a carriage mounted abutment means.

Linkage

The mattress shifting linkage is mounted on the table frame 9 along the shifting end of the table, under the north marginal leaf 15, and operates a lever 137 fixed to the underside of the west marginal leaf 16 near the north end of the table. The linkage comprises: a crank 138 journaled on a horizontal axis extending in a north-south plane through the table; a gear 139 rotated by the crank 138; a horizontal rack 140 slidably mounted on the frame 9 to extend in an east-west plane of the table and driven by the gear 139; and a link 141 connecting the west end of the rack 140 to the lever 137. Rotating the crank 138 clockwise, looking at FIG. 19, pushes the rack 140 and link 141 to the west, as shown in dotted lines, to raise the west marginal leaf 16 through its mattress shifting movement.

Carriage Abutment Means

As seen in FIG. 21, a horizontal lug 143 is slidably mounted on the carriage housing 5 to move between an outer position, in which it will clear the crank 138 and an inner position extending inwardly toward the base, in which it will strike the crank 138 as the carriage travels along the north end of the base.

In operating this modified mattress shifting means, the lug 143 is moved to its inner position before the carriage 5 reaches the shifting end of the table. Upon reaching the crank 138, the lug will turn the crank clockwise, as seen in FIG. 19, as it is carried past the crank by the carriage and the west marginal leaf 16 will swing through its mattress shifting movement. During the shifting of a mattress, the operator will disconnect the drive of the sewing head 6 by a suitable clutch and the shifted speed of the mattress will be equal to the carriage speed.

EXPANDED SCOPE OF INVENTION

While all aspects of the present invention may be fully utilized in a mattress sewing table of the described type, it will be appreciated that it is within the scope of this invention to provide the table leaves, the mattress shifting means and the mattress centering means with other types of movements, other than hinged movements. For example, these members could be moved bodily, rather than simply being swung about a fixed pivot, in either a purely sliding motion or a combination sliding and swinging motion.

It will also be appreciated that the mattress centering and shifting features and the other features involved in the second aspect of this invention are applicable to mattress edge sewing machines generally, rather than simply being limited to those tables employing means for elevating the margins of a mattress. For example, the mattress centering and shifting features of this invention may be advantageously employed in tape edge, roll edge and other types of mattress edge sewing machines conventionally comprising: a mattress supporting table; a carriage mounted on the table for movement around its periphery; a sewing machine mounted on the carriage; and carriage mounted drive means for moving the carriage and operating the sewing machine.

Having described my invention, I claim:

1. A table for supporting a mattress during the operation of closing its partly formed cover, comprising: a mattress supporting table structure including a table

top having horizontally spaced members arranged to engage oppositely disposed margins of a mattress resting on said top; means mounting said members on said table structure for movement to a relatively elevated position wherein they cooperate to support said mattress with all of its margins elevated and its center portion sagging; a sewing machine and carriage mounted on said table structure for movement around said table top; operating means mounted on said table structure for operation, when actuated, to move said mattress-support members to said elevated position, and means for actuating said table mounted operating means.

2. The table of claim 1 wherein: said members include a leaf hinged to said table top; and said operating means includes a fluid operated cylinder operably connected to said leaf for elevating it.

3. The table of claim 1 wherein: said means for actuating said table mounted operating means includes control means mounted on said carriage for movement therewith.

4. The table of claim 3 wherein said traveling carriage includes a support for the operator of said control means; and said control means includes a foot pedal mounted on the carriage for operation at the will of said operator.

5. The table of claim 1 including: centering means mounted on said table structure for movement, when actuated, from an out-of-the-way position to a mattress centering position, said centering means being operative, during said movement, to engage the peripheral border of a mattress on the table and, through such engagement, move it into a centered position; table-mounted means for operating said centering means, said operating means being operative, when actuated, to move said centering means to said mattress centering position; and means for actuating the said operating means for said centering means.

6. The table of claim 5 wherein: said centering means includes a centering element movably mounted on one of said horizontally spaced members; and said operating means for said centering means includes means for moving said centering element to its mattress centering position simultaneously with the elevating movement of its member.

7. The table of claim 6 wherein: said centering element is hingedly mounted on said one member for swinging movement between its out-of-the-way position and its centering position in which it extends upwardly from said member.

8. The table of claim 5 wherein: said means for actuating said operating means for said centering means includes control means mounted on said carriage for movement therewith.

9. The table of claim 1 including: shifting means mounted on said table structure for shifting movement, when actuated, from a first position to a second position, said shifting means being arranged to engage a mattress during such movement and, through such engagement, urge it across the table from one offset position to the other; table-mounted means for operating said shifting means, said operating means being operative, when actuated, to move said shifting means from said first position to said second position; and means for actuating said operating means for said shifting means.

10. The table of claim 9 wherein: said shifting means includes a shifting leaf hinged to said table structure for movement between said first and second positions; and said operating means for said shifting means includes a fluid operated cylinder mounted on the table structure for swinging said leaf between said positions.

11. The table of claim 10 wherein: said operating means for said shifting means includes means operative, in response to the arrival of said shifting leaf at said second position, to reverse the movement of said shifting leaf.

12. The table of claim 9 wherein: said means for actu-

ating said operating means for said mattress-support members, and for said shifting means includes control means mounted on said carriage for movement therewith.

13. The table of claim 9 including: centering means mounted on said table structure for movement, when actuated, from an out-of-the-way position to a mattress centering position, said centering means being operative, during said movement, to engage the peripheral border of a mattress on the table and, through such engagement, move it into a centered position; table-mounted means for operating said centering means, said operating means being operative, when actuated, to move said centering means to said mattress centering position; and means for actuating said operating means for said centering means.

14. The table of claim 13 wherein: each of the actuating means for actuating the table-mounted operating means for said mattress-support members, said centering means and said shifting means includes control means mounted on the carriage for movement therewith and for selective operation at the will of the operator.

15. The table of claim 14 wherein: the table structure has a starting end and a shifting end; the table-mounted operating means for said mattress-support members and said centering means is arranged for actuation from said carriage at the starting end of the table; and said control means is operable at the starting end of the table for actuating the operating means for said members and said centering means.

16. The table of claim 14 wherein: the table structure has a starting end and a shifting end; the table-mounted operating means for said shifting means is arranged for actuation from said carriage at the shifting end of the table; and said control means is operable at the shifting end of the table for actuating the operating means for said shifting means.

17. The table of claim 14 wherein: the table structure has a starting end and a shifting end; the several table-mounted operating means, which operate said means for shifting a mattress from said one side of the table to the other side thereof and for supporting and centering it on said other side are mounted on the table for actuation from said carriage at the shifting end of the table; and said control means for actuating said several table-mounted operating means is operable at the shifting end of the table.

18. A table for supporting a mattress during a sewing operation comprising: a mattress supporting table structure including a table top adapted to receive the mattress to be sewn in a position in which the mattress is approximately centered for the institution of the sewing operation; centering means mounted on the table structure for movement, when actuated, from an out-of-the-way position to a mattress centering position, during which movement it engages the peripheral border of the mattress and, through such engagement, urges it into a centered position; means for operating said centering means, said operating means being operative, when actuated, to move said centering means to said mattress centering position; and means for actuating said operating means for said centering means.

19. A table for supporting a mattress during the mattress sewing operation comprising: a supporting structure; a table top supported on said structure, said top being adapted to provide a support for a mattress which is offset to one side of said table during a sewing operation on that side and to the opposite side of said table during a sewing operation on said opposite side; shifting means mounted on said table for shifting movement, when actuated, from a first position to a second position, during which it operatively engages a mattress and, through such engagement, urges it across the table from one offset position to the other; means for operating said shifting means, said operating means being operative, when actuated, to move said shifting means from said first position to said second position; and means for actuating said operating means for said shifting means.

20. A table for supporting a mattress during the cover closing operation, comprising:
- A. a supporting structure;
  - B. a table top supported on said structure;
  - C. horizontally-spaced movable sections supported on said structure for movement between one position, in which they are respectively adjacent oppositely-disposed bottom-face margins of a mattress on said table top, and a relatively elevated position, in which they engage said bottom-face margins and, through such engagement, support said mattress with its aforesaid bottom-face margins elevated relative to its central portion and with its central portion in a sagging condition; and
  - D. means for moving each of said sections from one of its positions to the other.
21. The table of claim 20 wherein:
- A. said movable mattress-supporting sections form at least part of said table top and include marginal sections providing oppositely-disposed margins of said table top.

22. The table of claim 21 wherein:

- A. said oppositely-disposed marginal sections provide side margins and end margins of said table top.

23. The table of claim 21 for use in supporting a large size of mattress and a smaller size of mattress, wherein:

- A. said movable sections also include one intermediate table top section interposed between said marginal sections;

- B. said marginal sections cooperate, when elevated, to provide a support for holding a large mattress in one position; and
  - C. said one intermediate section and one of said marginal sections cooperate, when elevated, to provide a support for holding a smaller mattress in a second position.
24. The table of claim 23 wherein:
- A. said movable sections also include another intermediate table top section interposed between said marginal sections; and
  - B. said other intermediate section and the other of said marginal sections cooperate, when elevated, to provide a support for holding said smaller mattress in a third position.
